FIG. 1

FIG. 4

FIG. 2

FIG. 3

FIG. 1 is a front perspective view of a jewelry pendant or similar article showing my new design wherein the forward portion or triangle of the Star of David is elevated from the rearward triangle which is attached to the cross arm of the Christian cross;

FIG. 2 is a front elevation thereof on a reduced scale as viewed in the direction of line 2 of FIG. 1;

FIG. 3 is a rear elevation thereof on a reduced scale as viewed in the direction of line 3 of FIG. 1; and

FIG. 4 is a front perspective view of an embodiment of my new design of FIG. 1 wherein the Star of David is planar with respect to the Christian cross, the rear view being identical to the front.

I claim:

The ornamental design for a jewelry pendant or similar article, substantially as shown and described.
